WITNESS:

UNITED STATES PATENT OFFICE.

OTTO SCHUPPERT, OF ARRINGTON, KANSAS.

TONGUE-SUPPORTING MEANS.

Application filed January 22, 1923. Serial No. 614,280.

To all whom it may concern:

Be it known that I, OTTO SCHUPPERT, a citizen of the United States, residing at Arrington, in the county of Atchison and State of Kansas, have invented new and useful Improvements in Tongue-Supporting Means, of which the following is a specification.

The principal object of this invention is to take the weight of a wagon tongue or the like off the horse's neck by providing spring supporting means for the rear end of the tongue.

Another object of the invention is to make the tension of the spring means adjustable.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view of a portion of a wagon showing the invention in use.

Figure 2 is a section on line 2—2 of Figure 1.

Figure 3 is a section on line 3—3 of Figure 1.

In these views 1 indicates the front part of a wagon and 2 the tongue thereof which is connected with the wagon in the usual manner. In carrying out the invention I place a bracket 3 on the rear end of the tongue and connect therewith the middle

link of a chain 4 which has its ends connected with the coil springs 5. The other ends of these springs engage the eyes of bolts 6 which pass through holes in the angle brackets 7 and are adjustably connected with said brackets by the nuts 8. The brackets are bolted to the wagon by the bolts 9.

It will thus be seen that the springs can be adjusted to prevent the front end of the tongue from dropping to a position where its weight will be carried by the horse's neck.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

In combination with a horse drawn agricultural implement, its axle and its tongue, means for relieving the horses from the weight of the tongue comprising a pair of brackets connected with the front face of the axle, one at each side of the inner end of the tongue and below the level of the tongue, an eye bolt carried by each bracket, a spring having one end connected with the eye of each bolt, a chain connecting the inner ends of the springs together and a hook-shaped bracket on the inner end of the tongue and on the top face thereof engaging the middle link of the chain.

In testimony whereof I affix my signature.

OTTO SCHUPPERT.
